CARTRIDGE FEEDER AND ORIENTER

John H. Woodberry, Metuchen, N. J.

Application November 24, 1942, Serial No. 466,825

5 Claims. (Cl. 86—45)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a mechanism for removing cartridges singly from a hopper into which they have been thrown irrespective of their orientation—i. e., the direction in which the projectile end points—and feeding them with a predetermined orientation. In the accompanying drawings,

Fig. 1 is a top view of a machine employing a plurality of improved feeding and orienting mechanisms;

Fig. 2 is a top view, in enlarged scale of a single one of the said mechanisms;

Fig. 3 is an elevational section thereof taken on the line 3—3 of Fig. 2;

Fig. 4 is a view similar to Fig. 3 but showing only a portion thereof, and with certain of the parts in different position;

Fig. 5 is a vertical sectional view on the line 5—5 of Fig. 3;

Fig. 6 is a horizontal sectional view on the line 6—6 of Fig. 3;

Fig. 7 is an elevational section (similar to Fig. 3) but showing a modified form;

Fig. 8 is a bottom view of the modified form of Fig. 7, and

Fig. 9 is a bottom view of the slide member of Figs. 7, 8.

The machine shown in Fig. 1 has five units (designated A, B, C, D and E) of the novel feeder-orienter of this invention, although it is clear that a single unit, or a different number than shown, may be used. The cartridges are thrown promiscuously into hopper 10 (see especially Fig. 3), i. e., with the projectile end of the cartridges pointing in either direction (unoriented). It is the function of the mechanism to be described to remove the cartridges singly from hopper 10 (or the plurality of hoppers 10, Fig. 1) and to feed the single cartridge with its projectile end pointed in a predetermined direction (oriented). The hopper is provided with a breast plate 11 which causes the cartridges to become stacked in the well 12 of the hopper. The bottom of well 12 is closed by a floor plate 14 the right edge of which (as viewed in Fig. 3) extends to provide a ledge 14' somewhat wider than the largest cartridge diameter. The front plate 15 of the hopper is open at its lower portion to provide a mouth a, Fig. 3, considerably wider than the largest cartridge diameter. The bottommost cartridges in hopper well 12 are prevented from falling out of

the hopper by a spring plate 13 secured along its left edge (as viewed in Fig. 3) by rivets or other fasteners 13a, to the underside of the floor plate 14. The right portion of the spring plate is formed with a double bevel projection comprising a steep bevel 16 which forms a stop at the mouth a and a bevel 17 of less slope forming a lip at the distal edge of spring plate 13.

In front of mouth a (to the right in Fig. 3) is 10 a member 20 mounted on floor plate 14 for an extent of sliding movement towards, and away from, the hopper 10. Slide member 20 is conveniently made from a single piece of springy plate bent in the form of an elongated-U comprising an upper web 21 and a lower web 22. The distal edge (left, as viewed in Fig. 3) of lower web plate 22 is provided with a centrally-located (see Fig. 2) stop lug 23 tongued out of the plate.

As slide member 20 approaches (moving leftward, Fig. 3) the hopper, the leading edge of lower plate 22 contacts lip bevel 17 of spring plate 13 to depress the plate to the position shown in Fig. 4, to permit the slide member 20 to continue to its leftmost position (shown in Fig. 4). In 20 reaching its leftmost position, the leading edge of upper web 21 of slide member 20 inserts itself between the lowermost cartridge M of the stack and the rest of the stack. The plate material of which slide 20 is fabricated is preferably spring 25 plate, and the U-shape of the slide is made sufficiently elongated, so that sufficient pressure will be brought to bear between the distal ends of the web plates 21—22 to firmly grasp the lowermost cartridge M in the manner of tongs. As the slide 30 20 is returned (rightwardly, Figs. 3—4) the cartridge M grasped between tong plates 21—22 will be carried with it and withdrawn from the stack. It should be observed, best from Fig. 4, that the 35 double bevel portion 16, 17 is not released (to spring upwardly) until after the distal edge of the plates 21—22 and also the gripped cartridge M, have passed to the right thereof.

The lower web 21 of the tong slide 20 has a centrally located cut-out or recess 28 open at the 40 leading (or left) edge, which provides clearance for a fixed stop 18 projecting upward at one end of a strip 18' secured at its other end to the underside of floor plate 14. The tongued stop 23 of the tong slide 20 is in the form of a bridge or 45 inverted-U, see Fig. 5, to provide clearance for the fixed central stop 18.

As tong slide 20 returns rightward, with a cartridge (designated N in Fig. 3) grasped between its tong plates 21—22, the cartridge N, more 50 particularly, a central point thereof, contacts of

central stop 18. The primer end of a cartridge presents the largest diameter; it is consequently this end of the cartridge which is grasped by tong plates 21-22. As contact is made with central stop 18, the cartridge is turned angularly on the said grasping point (at the primer end of the cartridge) as a pivot, see cartridge P, Fig. 2. Cartridge P happened to be grasped in the tong slide with its primer end facing downward in the sheet, Fig. 2; hence cartridge P is turned in a counter-clockwise sense (as viewed in Fig. 2) by contact with central stop 18. Had the cartridge been oppositely oriented, it would have been turned in a clockwise sense. In either case, the projectile end of the grasped cartridge trails the slide (i. e., is to the left as the slide moves rightwardly).

Positioned somewhat to the right of the central stop 18, see Figs. 2 and 3, is a pair of side stops 19, conveniently tongued out of the side guides 9 in which member 20 slides. As tong slide 20 continues to move rightwardly—carrying cartridge P, now angularly turned, see Fig. 2—the primer end of the cartridge (which is always, as explained above, the leading end as the slide moves rightward) contacts one or the other of the side stops 19, see cartridge Q, Fig. 6. The side stops 19 are so positioned relative to the edges of tong plates 21-22 of slide 20 that the cartridge is pushed—by contact of a stop 19 with the primer end of the cartridge—off the slide, still in its angularly turned position (P, Fig. 2 and Q, Fig. 6) with the projectile end trailing. In this manner the cartridges are oriented to fall projectile end forward through a hatch or opening 8 provided in the floor plate 14.

The spring plate is shown in Figs. 1-6 in the form of a wide plate extending substantially the length of the hopper. Instead of a single, wide plate, a pair of spring fingers 33, Figs. 7-8, may be used. As shown in Figs. 7-8, the two fingers may be united by a brace strip 34.

One form of drive for the slide members 21 (five shown) is illustrated in Fig. 1. Each of the five slides 20 is connected by a rod 7 secured at one end to the slide and articulated at its other end to a short connecting rod 6 which is articulated to the crank arm 5 of a crankshaft 4. The crank arms 5 (and their slides 20) should preferably be distributed on the crankshaft to attain balance, as shown in Fig. 1, with substantially equal masses moving in opposite directions.

I claim:

1. In a device for feeding and orienting cartridges with their projectile ends pointed in a predetermined direction, in combination, a hopper for receiving dis-oriented cartridges and provided with a well designed to receive a single stack of cartridges, the front wall of the hopper being provided at the said well with an opening, a spring plate secured to the underside of the hopper and provided with a double bevel upward projection, the proximal bevel being of steeper inclination and serving to close the said opening and the distal bevel forming a lip of less inclination, a slide member in the form of an elongated-U excursionable towards and away from the said hopper well, the edge of the lower web of the slide member being adapted to cam the said lip of the spring plate downwardly to depress the said closing bevel away from the said well opening and the leading portion of the slide member being adapted to insert itself between the lowermost cartridge in the well and those

above it, the lower web being provided with a centrally located stop set back from its edge a distance commensurate with the cartridge diameter, the said U-shaped slide member being made of springy plate to grip the said lowermost cartridge at the distal ends of the webs against the said central stop whereby the gripped cartridge is removed rearwardly with the slide member, the lower web being provided with a centrally located recess, a stop fixed to the machine frame and projecting through the said recess, the said central stop of the lower web being in the form of an inverted U-bridge to provide clearance for the said fixed stop, whereby as the slide member is withdrawn a central point of the said gripped cartridge contacts the said fixed stop to turn the cartridge on its largest, primer end to point the projectile end foremost, a pair of fixed stops one at each side of the sliding member and positioned to the rear of the said central fixed stop and adapted to be contacted by the primer end of the said gripped and turned cartridge, to push the said cartridge off the slide member with its projectile end pointed forwardly.

2. In a device for feeding and orienting cartridges with their projectile ends pointed in a predetermined direction, in combination, a hopper for receiving dis-oriented cartridges and provided with a well designed to receive a single stack of cartridges, the front wall of the hopper being provided at the said well with an opening, a pair of spring fingers secured to the underside of the hopper and provided with double bevel upward projections, the proximal bevel being of steeper inclination and serving to close the said opening and the distal bevel forming lips of less inclination, a slide member in the form of an elongated-U excursionable towards and away from the said hopper well, the edge of the lower web of the slide member being adapted to cam the said lips of the spring fingers downwardly to depress the said closing bevels away from the said well opening, the leading portion of the upper web of the slide member being adapted to insert itself between the lowermost cartridge in the well and those above it, the lower web being provided with a centrally located stop set back from its edge a distance commensurate with the cartridge diameter, the said U-shaped slide member being made of springy plate to grip the said lowermost cartridge at the distal ends of the webs against the said central stop whereby the gripped cartridge is removed rearwardly with the slide member, the lower web being provided with a centrally located recess, a stop fixed to the machine frame and projecting through the said recess, whereby as the slide member is withdrawn a central point of the said gripped cartridge contacts the said fixed stop to turn the cartridge on its largest, primer end to point the projectile end foremost, a pair of fixed stops one at each side of the sliding member and positioned to the rear of the said central fixed stop and adapted to be contacted by the primer end of the said gripped and turned cartridge, to push the said cartridge off the slide member with its projectile end pointed forwardly.

3. In a device for feeding and orienting cartridges with their projectile ends pointed in a predetermined direction, in combination, a hopper for dis-oriented cartridges, the front wall of the hopper being provided with an opening, a spring plate secured to the underside of the hopper and provided with a double bevel upward projection, the proximal bevel being of steeper in-

clination and serving to close the said opening and the distal bevel forming a lip of less inclination, a slide member in the form of an elongated-U excursionable towards and away from the hopper, the edge of the lower web of the slide member being adapted to cam the said lip of the spring plate downwardly to depress the said closing bevel away from the said opening and the leading portion of the upper web of the slide member being adapted to insert itself between the lowermost cartridge in the hopper and those above it, the lower web being provided with a centrally located stop set back from its edge a distance commensurate with the cartridge diameter, the said U-shaped slide member being made of springy plate to grip the said lowermost cartridge at the distal ends of the webs against the said central stop whereby the gripped cartridge is removed rearwardly with the slide member, a stop fixed to the machine frame, whereby as the slide member is withdrawn a central point of the said gripped cartridge contacts the said fixed stop to turn the cartridge on its largest, primer end to point the projectile end foremost, a pair of fixed stops one at each side of the sliding member and positioned to the rear of the said central fixed stop and adapted to be contacted by the primer end of the said gripped and turned cartridge, to push the said cartridge off the slide member with its projectile end pointed forwardly.

4. In a device for feeding and orienting cartridges with their projectile ends pointed in a predetermined direction, in combination, a hopper for dis-oriented cartridges, the front wall of the hopper being provided with an opening, a spring plate secured to the underside of the hopper and provided with a double bevel upward projection, the proximal bevel serving to close the said opening and the distal bevel forming a lip, a slide member in the form of an elongated-U excursionable towards and away from the said hopper, the edge of the lower web of the slide member being adapted to cam the said lip of the spring plate downwardly to depress the said closing bevel away from the said opening, the leading portion of the upper web of the slide member being adapted to insert itself between the lowermost cartridge in the hopper and those above it, the lower web being provided with a centrally located stop set back from its edge a distance commensurate with the cartridge diameter, the said U-shaped slide member being made of springy plate to grip the said lowermost cartridge at the distal ends of the webs against the said central stop whereby the gripped cartridge is removed rearwardly with the slide member, the lower web being provided with a centrally located recess, a stop fixed to the machine frame and project-

10 ing through the said recess, the said central stop of the lower web being in the form of an inverted U-bridge to provide clearance for the said fixed stop, whereby as the slide member is withdrawn a central point of the said gripped cartridge contacts the said fixed stop to turn the cartridge on its largest, primer end to point the projectile end foremost, a pair of fixed stops one at each side of the sliding member and positioned to the rear of the said central fixed stop and adapted to be contacted by the primer end of the said gripped and turned cartridge, to push the said cartridge off the slide member with its projectile end pointed forwardly.

15 5. In a device for feeding and orienting cartridges with their projectile ends pointed in a predetermined direction, in combination, a hopper for receiving dis-oriented cartridges and provided with a well designed to receive a single sack of cartridges, the front wall of the hopper being provided at the said well with an opening, a spring plate secured to the underside of the hopper and provided with a double bevel upward projection, the proximal bevel serving to close the said opening and the distal bevel forming a lip, a slide member in the form of an elongated-U excursionable towards and away from the said hopper well, the edge of the lower web of the slide member being adapted to cam the said lip of the spring plate downwardly to depress the said closing bevel away from the said well opening, the leading portion of the upper web of the slide member being adapted to insert itself between the lowermost cartridge in the well and those above it, the lower web being provided with a centrally located stop set back from its edge a distance commensurate with the cartridge diameter, the said U-shaped slide member being made of springy plate to grip the said lowermost cartridge at the distal ends of the webs against the said central stop whereby the gripped cartridge is removed rearwardly with the slide member, the lower web being provided with a centrally located recess, a stop fixed to the machine frame and projecting through the said recess, whereby as the slide member is withdrawn a central point of the said gripped cartridge contacts the said fixed stop to turn the cartridge on its largest, primer end to point the projectile end foremost, a pair of fixed stops one at each side of the sliding member and positioned to the rear of the said central fixed stop and adapted to be contacted by the primer end of the said gripped and turned cartridge, to push the said cartridge off the slide member with its projectile end pointed forwardly.

JOHN H. WOODBERRY.

CERTIFICATE OF CORRECTION.

August 17, 1943.

Patent No. 2,326,816.

JOHN H. WOODBERRY.

It is hereby certified that error appears in the printed specification of the above numbered patent requiring correction as follows: Page 1, second column, line 55, for "contacts of" read --contacts the--; page 3, first column, line 5, claim 3, before "hopper" insert --said--; and second column, line 20, claim 5, for "sack" read --stack--; and that the said Letters Patent should be read with this correction therein that the same may conform to the record of the case in the Patent Office.

Signed and sealed this 14th day of September, A. D. 1943.

Signed and sealed this 14th day of September, A. D. 1943.
